APPARATUS AND METHOD FOR REMOVING
GAS FROM ENCLOSED AREAS

Edward Lamb, San Francisco, Calif.

Application June 1, 1936, Serial No. 82,707

13 Claims.

(Cl. 98—1)

This invention relates to apparatus and method for removing gas from enclosed areas and has for one of its objects the provision of a relatively light, portable device adapted to accomplish the removal of heat, smoke, or other gases from buildings, ships, sewers, mines, or other substantially enclosed areas by use of compressed air, steam, or the like, and which device is also adapted, if desired, to be used to force fresh air, or steam, or other gases, into such buildings, etc. Another object of my invention is the provision of a mobile fire-fighting unit comprising a power-driven vehicle carrying thereon my device above described, together with other equipment such as drills, air hammers, saws, masks, winches, etc., all of which are adapted to be operated from the same source of compressed air or steam, and in which my gas removing device is portable independently of the vehicle and source of compressed air or steam, but connected to said source for actuation thereof, and in which unit the motive power for moving the vehicle is adapted to supply the power for compressing the air or supplying the steam according to the character of said motive power.

Other objects and advantages will appear in the specification and drawing annexed hereto.

In the drawing, Fig. 1 represents a side elevational view of a fire truck, including my invention thereon, operatively connected thereto.

Fig. 2 is an enlarged view of my special portable device for removing gases and heat or for supplying fresh air to a particular point, as desired.

Fig. 3 is a reduced size elevational view of the device of Fig. 2 positioned horizontal and with an extension conduit connected thereto.

Fig. 4 is an enlarged fragmentary sectional view of the lower end of the device of Fig. 2 as seen from the line 4—4 of Fig. 5.

Fig. 5 is a sectional view as seen from the line 5—5 of Fig. 4.

In detail the apparatus as shown in Fig. 1 comprises a fire truck including wheels, chassis frame and body and a conventional power take-off operatively connected to the engine of the truck with a clutch lever 2 accessible to the driver for operatively connecting and for disconnecting the take-off from the engine. The driving shaft 3 from the power take-off carries a pulley 4 connected by a chain or belt 5 to a pulley 6 on a shaft arranged for operating an air compressor 7 from which the compressed air goes to a compressed air tank 8 and from the tank 8 to a purifier 9. From the tank 8 a valved air conduit 10

connects to a conventional hollow hose reel spindle to which spindle is connected one end of an air hose 11 that is normally coiled on the reel 12 and the other end of the hose connects to a hollow annular base of a tubular smoke and heat ejector generally designated 13, which is removably mounted on the truck.

A valved air line 14 leads from the air purifier to a rotatable reel of hose 16 connecting with the hollow spindle thereof as is ordinary in such reels, to which spindle one end of a hose line 17 extends for connecting at its opposite end to a reduction valve 18 from which valve a conduit conveys air under reduced pressure to the inside of a mask 19 for supplying air under pressure to the wearer when the mask is on a person. An auxiliary air purifier 20 is part of the mask assembly, which purifier is arranged for automatically opening a line to flow of air under atmospheric pressure to within the mask in the event of an obstruction to flow in line 17, and at the same time closes the inlet from the reduction valve into the mask. It is manifest that several air lines may connect to line 14 as through yokes or a branched fitting 21.

Also leading from the air purifier 9 is an air line 22 operatively connected to a conventional pneumatic winch 23 positioned at the forward end of the truck, and other line 24 leads to a reel of hose 25 at the rear end of the truck for supplying air to the hose through a hollow spindle rotatably mounting the reel in the same manner as reels 11, 16. The hose of reel 25 is operatively connected to a conventional air hammer, drill or pavement breaker 26 removably mounted on the rear end of the truck.

Preferably, a complete set of tools and reels as above described is provided on both sides of the truck, one side only being shown. The various air lines are suitably valved, as indicated in the drawing for closing off the air to any line as desired, or closing all of the lines when not in use. The power take-off, already described, is conventional, and is adapted to operate from the main truck engine when the truck is proceeding to the fire or is stationary, hence a satisfactory air pressure is quickly built up for immediate use of all pieces of fire equipment when the truck has arrived at the fire or at any point where the apparatus is needed.

The smoke and heat ejector 13 comprises an annular base 27 interiorly formed with an elongated continuous air passageway 28 therein in the general shape of an Archimedes spiral as indicated in Fig. 5, an air inlet 29 entering at

the enlarged diameter of the spiral from which inlet the air hose 11 extends for supplying air under pressure thereto.

- In the position of the ejector as indicated in Figs. 1, 2, and 4, the passageway 28 is in a horizontal plane. The upper wall 30 of the passageway is formed to extend upwardly at 31 adjacent the inner side of the spiral to form an annular upstanding collar with its inner sides tapering inwardly as they extend upwardly from wall 30 and an annular flange 32 projects outwardly around the upper edge of the collar and then upwardly at 33 around the outer edge of the flange.
15. Supported on and bolted to flange 32, is an annular collar 34 positioned in upward extension of the collar 31, which collar 34 has a flange 35 around its lower end for bolting to flange 32 by bolts 36, a gasket 37 being positioned between said flanges to form an air tight connection.

The radially inner wall of the spiral passageway curves upwardly to terminate in a cylindrical portion 38, spaced at its upper terminating edge about five thousandths of an inch from the inner side of the collar 34 and just above the tapered inner side of the collar 31, thus forming an annular, upwardly directed relatively small aperture for discharge of compressed air or steam entering the spiral passageway through inlet 29, 25 and secured to and extending upwardly from collar 34 is a tubular extension 39, the walls of which taper slightly outwardly from its point of connection with collar 34, the inner tapered surface being flush with, and in extension of 30 the inner surface of collar 34.

A handle 40 projects from a side of the tubular member 39 adjacent the base casting to permit carrying the ejector, and handles 41 are at the outer end of the tubular member to enable 40 several operators to manipulate the ejector as desired. Also a ring 42 with outwardly projecting lugs 43 is secured around the upper end of the tubular member for providing the lugs for a conventional bayonet joint for connecting a hose 44 of canvas, rubber, or the like, capable of being coiled or rolled up when not in use or tubular extension to the outer end of the member 39, the hose having a conventional coupling at one end internally recessed in the usual way for 45 providing the female member for receiving lugs 43. In certain installations it is highly desirable that a tripod 44 be provided for supporting the ejector horizontally.

From the foregoing, it will be seen that my 55 ejector, when compressed air is admitted to the spiral passageway 28, operates on the induction jet principle. The base member is formed to provide an annular nozzle and induces a flow of air, smoke, or other gases, including heat, 60 through the member 39.

In actual practice, one of my devices, formed with a .005 inch ejection orifice and approximately a 6 inch throat diameter with an overall length of 36 inches and with the outer end 65 of the member 39 approximately 10 inches in diameter, has a Venturi displacement of 4400 cubic feet per minute at the rate of 73 miles per hour with compressed air at only 100 lbs. pressure.

In a recorded test, the base end of the device 70 was placed through an opening in the wall of an ordinary room with a fire burning therein, and filled with smoke. The temperature within the room was 135° F. and only three minutes elapsed from the time the smoke ejector commenced operation until the smoke was ejected

out of the room and the temperature reduced to 78° F. when the firemen entered and extinguished the fire. The room was 21 x 11 x 8 feet.

In a room 30 x 12 x 8 feet with the temperature 140° F. and filled with smoke and fire, the ejector removed the smoke, reduced the temperature to about 80° F. and the fire extinguished in less than four minutes from the time of entry and the ejector was then reversed to blow fresh air into the room clearing the same of all traces 10 of smoke and fumes in another two minutes.

Heretofore, where fire has started in basements, substantially enclosed rooms, or in the holds of ships, or where dangerous gas has accumulated or is released from broken pipes, there 15 has been no effective manner of clearing the rooms or compartments or of forcing fresh air into places after the removal of gases. Also the intense heat, where fire is in the rooms or compartments, has precluded the opportunity for 20 firemen to enter and to work effectively. The rapid and large displacement of smoke, fumes, heat, etc., from such rooms by my device, not only accomplishes the result of clearing the room 25 of smoke and heat, but functions to reduce combustion since it reduces the supply of oxygen to the flames. By extending the length of the tubular member 39, its efficiency can be greatly increased, where necessary, although the device without the extension is normally satisfactory. 30

I therefore claim:

1. The method of removing or clearing rooms or enclosed areas of smoke, dangerous gases or heat comprising the steps of conducting air under compression to the room from a remote 35 source of compressed air and ejecting the compressed air through an air induction nozzle at the room in a direction outwardly of the room for inducing a flow of gas through the nozzle from within the room to outside the room for 40 clearing the room of said gas, followed by the step of reversing the position of the air induction nozzle and directional flow of compressed air therethrough for inducing a flow of fresh air through the nozzle from outside the room to 45 within the room.

2. Fire fighting apparatus comprising a vehicle, an air compressor thereon, means for operating the compressor, a compressed air-operated air induction device formed with a Venturi-shaped open ended passageway and an annular discharge aperture adjacent the throat and around the inner side of the passageway arranged for discharging compressed air into the passageway toward one open end of the passageway whereby outside air will be induced to flow into the passageway through the opposite open end and through said passageway and out of the first mentioned open end, a flexible extensible compressed air line connecting between the compressor and said device, said device being removable from the vehicle independently of the compressor and being portable for positioning said device with said opposite open end in communication with the inside of a room and with 60 the first mentioned open end directed outwardly of the room for inducing an outward flow of air, including gas or heat from the room upon actuation of the device. 55

3. Apparatus for removing gas from a room 70 comprising an elongated body formed with an open ended bore extending longitudinally therethrough, one open end thereof forming a gas inlet and the opposite open end thereof forming a gas outlet and the bore being of enlarged di- 75

diameter at its opposite open ends tapering toward each other to form a restricted throat at a point intermediate the opposite ends thereby providing a bore of substantially Venturi-shape, said body being provided with an annular chamber for compressed air disposed around the bore adjacent the throat, and the walls of the bore adjacent the throat being formed with an annular aperture extending therearound communicating 10 between the chamber and bore, said aperture opening into the bore in the direction of the outlet end thereof, a source of compressed air, a flexible, extensible, air line connecting between the chamber and source of compressed air, said 15 body being portable independently of the source of compressed air for positioning in any desired position within the room with the outlet directed outwardly of the room whereby upon ejection of compressed air from the chamber through 20 said aperture and into the bore the gas within the room will be induced to flow through the bore from the inlet to the outlet and out of the room.

4. In a construction as defined in claim 3, an 25 elongated open ended cylindrical tube secured at one end to the outlet end of the body, said tube arranged with the bore thereof forming an extension of the bore of the body, means releasably securing said tube to the body.

5. In a construction as defined in claim 3, an 30 elongated open ended cylindrical tube secured at one end to the end of the body, said tube arranged with the bore thereof forming an extension of the bore of the body, said tube being of 35 flexible material adapted to be rolled up longitudinally thereof, when the apparatus is not in use and means releasably securing said tube to the body.

6. In a construction as defined in claim 3, said 40 body being formed at the inlet end to provide an enlarged base around the inlet for supporting the body vertically thereon.

7. In a construction as defined in claim 3, a 45 wheeled vehicle, said body being removably supported therein when not in use, said source of compressed air being stationarily mounted on said vehicle, said flexible air line comprising a hose operatively connected at one end with the body for admitting air to the chamber, and means 50 operatively connecting the opposite end of the hose with the source of compressed air for admitting air to the hose including a reel arranged and adapted for winding the hose thereon and for unwinding the hose therefrom without dis- 55 connecting the operative connections of the hose with the body and source of compressed air whereby the body may be removed from the vehicle to points of various distances from the vehicle for use at such points.

8. A device for removing gas from any desired 60 area comprising an open ended, elongated tube, the walls of the bore of said tube tapering from opposite ends thereof of enlarged diameter to a reduced diameter at a point intermediate said 65 ends thereby forming a restricted throat portion at said point, said tube being provided with an annular chamber encircling the tube adjacent the throat portion thereof and the walls of the bore of the tube adjacent the throat portion being 70 formed to provide an annular aperture encircling the bore and communicating between the chamber and bore, an air inlet for admitting compressed air to said chamber for ejection therefrom through the aperture, and the opposite sides 75 of the aperture around the length thereof being

formed to direct the air ejected therethrough into the bore along lines extending substantially parallel with the walls of the bore in a direction toward one of said open ends of the tube, an air line connected with the air inlet of the chamber for conducting air under pressure to said chamber, said tube being freely movable to various positions and the air line being flexible for permitting movement of the tube to different areas or to various positions relative to a predetermined area as may be desired.

9. In a construction as defined in claim 8, the cross-sectional area of said aperture being substantially uniform at any point around its length and the distance between adjacent sides of the aperture at any point around the length thereof being not more than .005 of an inch, said chamber being of progressively reduced cross-sectional area from a point at the air inlet in a direction therefrom around the circumference to a point 20 adjacent said air inlet.

10. In apparatus of the character described, an elongated, open-ended Venturi-tube having the restricted throat of the bore thereof disposed adjacent one of the open ends of the tube and remote from the opposite open end thereof, the walls of said bore being formed to provide an annular aperture extending therearound adjacent the throat, said aperture opening into the bore in the direction of the open end of the tube 25 remote from the throat, and the aperture being formed to eject fluid therethrough into the bore at all points therearound along lines extending substantially parallel with the walls of the bore between the aperture and said remote end whereby fluid ejected into the bore through said aperture at points at opposite sides of the bore will tend to move directly toward said remote end along non-intersecting paths, a source of fluid 30 under pressure, said tube being movable independently of said source, and means connecting between said source and said aperture for conducting fluid under pressure to said aperture, said means including a flexible fluid pressure line for 35 permitting movement of said tube to various positions as desired.

11. An ejector nozzle comprising an elongated, tubular body having an open-ended bore extending longitudinally therethrough, one open end of said body forming an inlet and the opposite open end forming an outlet, said bore being of enlarged diameter at the inlet and outlet ends, thereof and of reduced diameter at a point relatively close to said inlet end, the walls of said bore extending oppositely outwardly from said point of reduced diameter to the inlet and outlet ends respectively being of progressively increased diameter whereby the bore is of generally Venturi shape with a throat portion at the point of reduced diameter, an annular aperture extending circumferentially 55 completely around the bore at said throat portion and opening into said bore in a direction substantially parallel with the central longitudinal axis of said bore, said throat portion being disposed relatively close to said inlet end and relatively remote from said outlet end and the degree of taper of the bore between said aperture and outlet end being relatively small whereby fluid under pressure ejected into the bore through said aperture will flow along the walls of the bore 60 toward the outlet upon being ejected through the aperture in a direction substantially parallel with said axis, means for conducting fluid under pressure to said aperture including a fluid pressure line constructed and arranged to permit bodily 65

movement of the nozzle to various points while the fluid is conducted through the line to said aperture, and said nozzle being relatively light and free from positive securement in a fixed position for permitting manual positioning of the nozzle to various positions as desired.

12. An ejector nozzle comprising a pair of generally frusto-conical tubular members secured together and positioned with their bores in axial alignment, the smaller diameter end of one of said members being disposed in spaced telescopic relation within the smaller diameter end of the other member, the diverging inner sides of the bore of said other member being straight from the enlarged diameter end thereof to and including the portion disposed in opposed spaced relation to the smaller diameter end of the first mentioned member and the opposed adjacent faces of the smaller diameter ends of the members being substantially parallel whereby said opposed adjacent faces form the opposite sides of an annular aperture adapted to direct air passing be-

tween said sides from outside the members into said other member in a direction toward the enlarged diameter end of said other member and along lines substantially parallel with the inner sides of the wall of said other member, and means for conducting air under pressure to said aperture for discharge therethrough, said nozzle being free from securement to a fixed position and the means for conducting air to said aperture including a flexible air line connecting with the nozzle for permitting movement of the nozzle to various positions while the air is being conducted to the aperture through the air line.

13. In a construction as defined in claim 12, said other member being appreciably longer than the first mentioned member and the opposite outer ends of both members being approximately of the same inside diameter, and means on the nozzle for manually grasping by a hand of an operator for moving the nozzle to various positions as desired.

EDWARD LAMB.
